(No Model.)

W. KOENEN.
STREET RAILROAD SWITCH.

No. 427,089.

Patented May 6, 1890.

UNITED STATES PATENT OFFICE.

WILLIAM KOENEN, OF CLEVELAND, OHIO, ASSIGNOR OF ONE-HALF TO
DE FRISTE VOGT, OF SAME PLACE.

STREET-RAILROAD SWITCH.

SPECIFICATION forming part of Letters Patent No. 427,089, dated May 6, 1890.

Application filed August 21, 1889. Serial No. 321,446. (No model.)

To all whom it may concern:

Be it known that I, WILLIAM KOENEN, of Cleveland, in the county of Cuyahoga and State of Ohio, a subject of the King of Prussia, have invented a new and useful Improvement in Automatic Street-Railroad Switches; and I do hereby declare that the following is a true, full, and exact description thereof.

My invention relates to automatic street-railroad switches; and the improvement consists in the peculiar construction and arrangement of the actuating mechanism thereof.

That the invention may be fully seen and understood, reference will be had to the following specification and the accompanying drawings, in which—

Figure 1 is a plan view of a railway-track and branch thereof provided with the switching mechanism above referred to. Fig. 2 is a vertical transverse section on line $x x$. Fig. 3 is a longitudinal section on line $x' x'$, and Fig. 4 is a vertical transverse section on line $y y$ of Fig. 1. The three last-named figures are enlarged with reference to Fig. 1.

Like letters of reference denote like parts in the drawings and specification.

In Fig. 1, A A represent the main track, B B a branch therefrom, and C the switch-rail for said branch. Arranged in connection with said switch-rail C is an underground shifting mechanism, which is operated by means of wheels secured to the front axle of the cars. Substantially said shifting mechanism consists of the line-shaft D, the lever E, with connecting-bar F, and the lever G, with tappets H H', Figs. 2, 3, and 4. The said shaft is arranged within the tube I, and the levers with appendages within the casings J and K, to protect said parts and to allow of their free movement therein. The tube I extends between said casings, and the shaft D is guided in the bearings a and b of the sides thereof, as seen in Fig. 3, while the levers are secured to the free ends of said shaft. Each of said casings is provided with a lid c and d , to admit of placing and arranging the working parts therein. The arm e of the connecting-bar F extends through slots in the casing J and the guard-rail L and connects with the switch-rail, as seen at f , and the opposite end

of said bar is pivoted to the lever F, as seen at g . Underneath said bar is journaled the roller M in a manner so as to assure a free movement of the switch-rail.

The tappets H H', which are located within the casing K, engage with their slotted shanks h over the pins i of the two-armed lever G at the front end of the shaft D. The upper part or head j of said tappets projects through and is guided in the openings k , which the lid d , in connection with the notched face-plate l , forms, as seen in Figs. 1 and 2. To the lever G is secured the tension-plate N, and it is the free ends thereof upon which the tappets are carried. The connection of tappets and lever is to a certain degree elastic, and thereby undue strains upon the levers or shaft, prevented. Said plate, however, is made sufficiently strong or stiff, so as not to yield before the switch-rail C is moved from one side to the other within the guard-rail L, and then only when the switch-rail comes to bear on either side of the guard-rail and the corresponding tappet is still further depressed by the passing wheel O on the front axle of the cars. Said tension-plate will yield, and thus save the diverse parts of the shifting mechanism from being damaged. The face-plate of the casing K is provided with flaring flanges m , into which the wheel O enters before depression of the tappet takes place. Said flanges serve the double purpose—viz., as a guide for the passing wheel and protection of the raised tappet. The tappets are so set in relation to the switch-rail that in whatever position said switch-rail may be one of said tappets projects out far enough through the opening k to move the rail when depressed sufficiently far enough in the direction which it has under control.

In Fig. 3 the cover d of the casing K is removed to enable a full side view of the tappet H'. For illustration, it is supposed that the switch-rail C is set for the side track B B. In that instance the tappet H' is raised, as shown in Figs. 2 and 3. Thus the approaching car, if intended to proceed on the main track, will enter with its wheel O on the side where the tappet H' is located and depress the same, which results in turning the lever F in direc-

tion of the arrow, Fig. 4, and in moving the switch-rail C by means of the connecting-bar F until said rail strikes the opposite side of the guard-rail L, which allows the car to pass on, as desired. Simultaneously with depressing the tappet H' the tappet H is raised for being depressed by the wheel of the car proceeding toward the branch track.

By the above-described means each car is enabled to set the switch-rail in advance automatically, so as to readily proceed on its intended route when approaching the switch.

What I claim, and desire to secure by Letters Patent, is—

15 1. In combination, the switch-rail, the tappet H, the shaft D, connections therefrom to

the switch-plate, and the yielding plate N, connecting the shaft with the tappet, substantially as described.

2. The combination of the switch-rail of a street-railroad, the shaft D, single lever E, with connecting-bar F, and the two-armed lever G, with tappets H H', said connecting-rod being supported upon a roller and the tappets resting upon a tension-plate, as shown, 20 and for the purpose described.

In testimony whereof I affix my signature in presence of two witnesses.

WILLIAM KOENEN.

Witnesses:

P. L. BAUM,

H. C. McDONALD.
